UNITED STATES PATENT OFFICE

2,600,006

FIRE ALARM

Stephen Kuzmich, Jr., Bayonne, N. J., assignor of
thirty per cent to John Kuzmich, Bayonne,
N. J.

Application September 14, 1949, Serial No. 115,676

3 Claims. (Cl. 177—358)

1

This invention relates to fire alarms, and more particularly to a fire alarm system which, when placed in a large building or community, will indicate at a central station, the exact location of a fire.

An object of this invention is to provide a fire alarm system which will indicate at a central station the precise location of a fire or an area of excessive temperature.

Another object of this invention is to provide a unit which may be readily and easily installed in a removable manner in a fire alarm circuit, and which is simple in operation.

A further object is to provide an improved signal block having signal resistances which may be readily inserted in the block in a removable manner.

These, together with the various ancillary objects which will become apparent as the following description proceeds, are attained by this fire alarm, a preferred embodiment of which has been illustrated, by way of example only, in the accompanying drawing, wherein:

Figure 1 is an elevational view of the contact unit adapted to be inserted in the fire alarm system, which is shown with its insulated case in section;

Figure 2 is a perspective view of the signal block forming one element of the present invention;

Figure 3 is a circuit diagram showing the connections of the signal units in the circuit with the central station;

Figure 4 is a partial elevational view of a dial as at the central station; and,

Figure 5 is a perspective view, parts being broken away and shown in section to show other parts more clearly, of a signal resistance used in connection with the signal block of the present invention.

With continued reference to the accompanying drawing, wherein like reference numerals designate similar parts throughout the various views, 10 generally designates an insulated case in which the signal unit generally designated by reference numeral 11 is encased.

Journaled to one side wall of the insulated container 10 is a shaft 12 having a stop member 14 secured thereto and extending at right angles therefrom. Connected to the shaft is a means for inducing rotary motion thereto which may be a weight 16 to which a cord or line 18 may be tied and thence connected to the shaft at its other end. The bimetallic thermostat 20 is secured to the case 10 by means of a standard

22 or other suitable mount. The stop 14 is adapted to be engaged by the thermostat 20 during such times until the thermostat is bent downward and out of the way of the stop due to subjection to a temperature above a defined limit. Supports 24 and 26 are used to retain the shaft and support it.

Secured to the standard 26 is an arm 28 which has a brush 30 attached thereto. A connecting wire 32 is secured to the brush and in turn, is connected to one of a pair of male prongs 34 and 36 which extend through a thickened portion 38 in the insulated case 10. The brush 30 engages a slip ring 40 at the end of the shaft 12 to which a brush 42 is attached. The commutator brush or contact brush 42 engages the surface of the signal bar generally designated by reference number 44.

The signal bar 44 comprises a front plate having a core 46 and a plurality of sections connected to the core in annularly spaced relationship such as those designated by reference numeral 48, 50, 52, 54 and 56. The core and sections of the front plate are made of an insulative material. A rear plate 58 is secured to the front plate and is much thinner than the thickened front plate. By means of a screw 60 extending through the case 10 the plates 44 and 58 are held in an abutting relationship. 20 Securely fastened to the front plate and the rear plate is a first conductor 62. A plurality of selected signal resistances as are indicated by reference numeral 64 are removably secured in the gaps left between the sections such as 50 and 52 and have their end plates 66 abutting against the rear plate 58. The rear plate is connected by conductor 68 to the prong 36.

Referring now more particularly to Figure 5, it will be seen that the signal resistances comprise a pair of electrically conductive plates 70 and 66. Between these plates is interposed a selected resistance coil 72. An insulative top and sides such as those indicated by reference numeral 74 are used to complete the signal resistance elements. The resistance elements 72 of the signal resistances 64 are made in varying resistances. These resistances are so designed that they will reduce the voltage across the lines to anyone of ten voltages used to represent members in a circuit where there is an electric power source herein shown as a generator 81, signal units 12 and a central station comprising a rheostat 76 and a voltmeter or galvanometer 78 positioned across the terminals of the line. A bell alarm 80 is also placed in circuit with the source

81 of electric power. A manually operated switch 82 is placed across the leads to the bell 80. The voltage drop across the lines which is readable on the voltmeter 78 is caused by having the brush 42 contact one of the resistances 72. This voltage drop will be read on the voltmeter since the current supplied by the source of power supply will remain standard, and the voltage therefore will depend on resistances in the circuit. A rheostat 76, of course, is provided to adjust the voltage reading at a prescribed standard resistance in the line to read a certain designated amount.

Each of the signal resistances 64 has a resistance 72 therein which will cause a voltage reading on the voltmeter corresponding to a numeral desired. Thusly, if a signal resistance is to designate a numeral, as for example, 6, it will be of such magnitude as to cause a voltage reading on the galvanometer with the indicator 84 thereon reading the numeral 6 on the scale 86. Accordingly, when the brush is rotated over the surface of the signal block, after actuation and release by the thermostatic element 20, it will contact a variety and plurality of the different signal resistances 64. As the brush contacts the resistances, the numerals on the scale 86 will be successively indicated by the pointer 84 in accordance with the magnitude of the resistances 72 in each of the signal resistances 64. As these numbers read may be used to indicate the location of various areas to be protected, an alarm designating the location of a fire may be given. When the switch 82 is set in an open position, upon contact of the brush with the signal resistances the aural alarm will be activated. A discriminating relay is placed in the circuit with the manual switch 82 to actuate it upon a drop of the voltage across the line. This discriminating switch may be of any well known design and is not shown.

Since from the foregoing, the construction and advantages of this fire alarm are readily apparent, further description is believed to be unnecessary.

However, since numerous modifications will readily occur to those skilled in the art after a consideration of the foregoing specification and accompanying drawings, it is not intended to limit the invention to the precise embodiment of fire alarm shown and described, but all modifications and equivalents may be resorted to which fall within the scope of the appended claims.

Having described the invention, what is claimed as new is:

1. A fire alarm system comprising a shaft, a stop member on said shaft, drive means secured to said shaft, a thermostatically actuated member selectively retaining and releasing said stop member, a contact brush operatively engaging a signal block comprising a front plate of electrically insulative material having a core and annularly spaced sections, a rear plate of electrically conductive material connecting means holding said plates together, resistance elements insertable between said annularly spaced sections in said front plates and extending therebetween, said resistance elements including spaced front and rear conductor plates, selected resistance coils

electrically connecting said conductors, electrically insulative top, bottom and side plates secured to said front and rear plates, a conductor connected to said core of said back plate, said conductor being connected in series to a voltmeter and to one terminal of a constant current source of power, said brush being electrically connected to the other terminal of said voltmeter and source of power.

10 2. A fire alarm system comprising a power source, a support, a plurality of impedance elements of differing impedance mounted on said support in fixed relation to each other and to said support, means electrically connecting one terminal of each of said impedance elements to said source of power, a contact brush rotatably mounted on said support and movable to selectively and progressively contact the other terminal of each of said elements, means for rotating said brush, thermal responsive means for controlling rotation of said brush, means electrically connecting said brush to said source of power, and means in said system for indicating the relative magnitude of the impedance element, a shaft, 20 said brush being carried by said shaft, said brush rotating means including a cord wound around said shaft and a weight on one end of said cord.

25 3. A fire alarm system comprising a power source, a support, a plurality of impedance elements of differing impedance mounted on said support in fixed relation to each other and to said support, means electrically connecting one terminal of each of said impedance elements to said source of power, a contact brush rotatably 30 mounted on said support and movable to selectively and progressively contact the other terminal of each of said elements, means for rotating said brush, thermal responsive means for controlling rotation of said brush, means electrically connecting said brush to said source of power, and means in said system for indicating the relative magnitude of the impedance element, a shaft, 35 said brush being carried by said shaft, said brush rotating means including a cord wound around said shaft and a weight on one end of said cord, said thermal responsive means including a unidirectionally yieldable finger on said shaft, and a thermal responsive element normally disposed in the path of travel of said finger and movable in response to a predetermined temperature out of the path of travel of said finger.
